(57) **CLAIM**

The ornamental design for a monitor, as shown and described.

DESCRIPTION

FIG. 1 is a front perspective view of a monitor, showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a rear perspective view thereof;

FIG. 9 is another front perspective view of a monitor of FIGS. 1-8, shown with the lower portion removed for ease of illustration;

FIG. 10 is a front view of the monitor shown in FIG. 9;

FIG. 11 is a rear view of the monitor shown in FIG. 9;

FIG. 12 is left-side view of the monitor shown in FIG. 9;

FIG. 13 is a right-side view of the monitor shown in FIG. 9;

FIG. 14 is a top view of the monitor shown in FIG. 9;

FIG. 15 is a bottom view of the monitor shown in FIG. 9;

FIG. 16 is a rear perspective view of the monitor shown in FIG. 9;

FIG. 17 is an enlarged view of the portion 17 in FIG. 2;

FIG. 18 is an enlarged view of the portion 18 in FIG. 3;

FIG. 19 is an enlarged view of the portion 19 in FIG. 5; and, FIG. 20 is an enlarged view of the portion 20 in FIG. 5.

The even-dash broken lines representing portions of the Monitor form no part of the claimed design. The dot-dot-dash broken lines encircling enlargement portions of the monitor form no part of the claimed design.

1 Claim, 20 Drawing Sheets
